UNITED STATES PATENT OFFICE.

SIGMUND BENENSOHN, OF YORKVILLE, ILLINOIS.

DESIGN FOR A CHARM.

SPECIFICATION forming part of Design No. 31,427, dated August 22, 1899.

Application filed July 29, 1899. Serial No. 725,544. Term of patent 7 years.

To all whom it may concern:

Be it known that I, SIGMUND BENENSOHN, a citizen of the United States, residing at Yorkville, in the county of Kendall and State of Illinois, have invented and produced a new and original Design for a Charm, of which the following is a specification.

The invention relates to a new and original design for a charm; and it has for its object 10 to provide an ornamental and attractive design of this character for a secret society.

The essential feature of the design resides in a body of approximately the shape of a shield and bearing a representation of a hand 15 grasping an ax-head, a leaf, and a maul and wedge.

In the drawings, Figure 1 is a perspective view of a charm, showing my new and original design. Fig. 2 is a rear elevation.

20 Referring to the drawings, 1 designates a body of approximately the shape of a shield provided at its front face with a representation of a hand grasping the head of an ax. The ax-head 2 is arranged in the palm of the 25 hand in an inclined position, the fingers 3 of the hand 4 being at the upper edge of the ax-

head and the thumb 5 at the lower edge. This representation is located at one side of the lower portion of the body 1, which is provided at the opposite side with a representation of 30 a leaf, the leaf 6 being in an upright position. On the face of the ax-head, near the lower corner thereof, is a maul 7 and a wedge 8, the wedge being disposed across the handle of the maul. The upper portion of the body is 35 ornamented with five jewels 9, representing stars, but these do not form an essential feature of the design. The design, which is an emblem of a secret society, can of course be applied to badges, pins, and the like, as will 40 be readily understood.

What is claimed is—

The design for a charm herein shown and described.

In testimony that I claim the foregoing as 45 my own I have hereto affixed my signature in the presence of two witnesses.

SIGMUND BENENSOHN.
